US00D798815S

(12) **United States Design Patent** (10) **Patent No.:** **US D798,815 S**
(45) **Date of Patent:** **** Oct. 3, 2017**

(54) **BATTERY UNIT**

(71) Applicant: **CONROY MEDICAL AB**, Upplands Väsby (SE)

(72) Inventors: **Lars Håkansson**, Stockholm (SE); **Anders Krook**, Stockholm (SE); **Erik Verrier**, Johanneshov (SE)

(73) Assignee: **CONROY MEDICAL AB**, Upplands Väsby (SE)

(**) Term: **15 Years**

(21) Appl. No.: **35/500,255**

(22) Filed: **Oct. 21, 2015**

(80) **Hague Agreement Data**

Int. Filing Date: **Oct. 21, 2015**
Int. Reg. No.: **DM/088013**
Int. Reg. Date: **Oct. 21, 2015**
Int. Reg. Pub. Date: **Nov. 6, 2015**

(30) **Foreign Application Priority Data**

Apr. 21, 2015 (EM) 002685859-0001

(51) **LOC (10) Cl.** **13-03**

(52) **U.S. Cl.**

USPC **D13/130**

(58) **Field of Classification Search**

USPC D13/130, 112, 116, 139.4, 152, 108;
312/111; 361/641

CPC A47B 47/0041; H02B 1/52
